Primary Examiner—Louis S. Zarfas*Attorney, Agent, or Firm*—Banner, Birch, McKie & Beckett**[57] CLAIM**

The ornamental design for an outsole, as shown and described.

DESCRIPTION

FIG. 1 is a bottom plan view of an outsole showing my new design;

FIG. 2 is a cross-section taken along lines 2—2 of FIG. 1;

FIG. 3 is a cross-section taken along line 3—3 of FIG. 1;

FIG. 4 is a cross-section taken along line 4—4 of FIG. 1;

FIG. 5 is a cross-section taken along line 5—5 of FIG. 1;

FIG. 6 is a cross-section taken along line 6—6 of FIG. 1;

FIG. 7 is a cross-section taken along line 7—7 of FIG. 1;

FIG. 8 is an elevational view of one side of the outsole shown in FIG. 1; and,

FIG. 9 is an elevational view of the other side of the outsole shown in FIG. 1.

The broken line showing of an upper in FIGS. 8 and 9 is for illustrative purposes only and forms no part of the claimed design.
